(57) **CLAIM**

The ornamental design for a sole for footwear, as shown and described.

DESCRIPTION

FIG. 1 is a front view of a sole for footwear;

FIG. 2 is a back view thereof;

FIG. 3 is a right-side view thereof;

FIG. 4 is a left-side view thereof;

FIG. 5 is a top view thereof; and,

FIG. 6 is a bottom view thereof.

The broken lines immediately adjacent the solid line portions of the design define the bounds of the claimed design and form no part thereof.

1 Claim, 6 Drawing Sheets
